ARTICLE SUPPORTING SPRING CLIP

Harry M. Price, Sr., Leavenworth, Kans.

Application August 31, 1953, Serial No. 377,393

2 Claims. (Cl. 24—84)

This invention relates to a spring clip of extremely simple construction and which is primarily adapted for use in supporting indicia bearing cards.

More particularly, it is an aim of the present invention to provide a spring clip for mounting cards, tags or labels on various articles or parts and which accordingly readily adapts itself for the mounting of price and display tags on merchandise and identification cards, tags or labels on various mechanical and electrical parts to facilitate assembly and repair.

Another object of the invention is to provide a spring clip capable of being readily attached to or detached from an article and to which an identifying tag, card or label may be readily applied or removed.

Another object of the invention is to provide a spring clip which may be very economically manufactured from a single strand of wire entirely by a machine operation and which will be extremely durable and efficient in accomplishing its intended result.

Other objects and advantages of the invention will hereinafter become more fully apparent from the following description of the drawing, illustrating a presently preferred embodiment thereof, and wherein:

Figure 1 is a side elevational view showing the spring clip in an operative position;

Figure 2 is a view taken at a right angle to Figure 1 and looking from right to left thereof, the tag being shown in section, and

Figure 3 is an enlarged sectional view taken substantially along a plane as indicated by the line 3—3 of Figure 1.

Referring more specifically to the drawing, the spring clip in its entirety and comprising the invention is designated generally 5 and is formed from a single strand or length of resilient or spring wire. Said strand or length of spring wire is wound near to but spaced from one end thereof to form a spring or torsional coil 6. The longer end of the wire strand extends outwardly from one end of the coil 6 to provide an anchored leg 7 of an elongated loop 8 having a turned back bend 9 at the opposite outer free end of said loop 8 and a second leg 10 extending back from the bend 9 past the opposite end of the coil 6. Said return leg 10 preferably has an inwardly bowed portion 11 located close to said last mentioned end of the coil 6 and is flared outwardly therebeyond and bent to provide a rounded tag, card or label supporting loop 12 which projects from the coil 6 in the opposite direction to said loop 8. The other unattached end 13 of the loop 12, constituting one terminal of the spring wire, terminates adjacent the first mentioned end of the coil 6 from which the leg 7 projects, as best seen in Figure 2.

The loop 8 constitutes one spring biased jaw of the clip 5. The outer portions of the legs 7 and 10 thereof, extending inwardly from the bend 9, are disposed substantially coplanar and have undulating formations to provide a recess 14 in said jaw 8 formed by substantially V-shaped portions of the legs 7 and 10 which are spaced from the outer end 9 of the jaw 8. The portions of the

legs 7 and 10 disposed between the bend 9 and the adjacent end of the recess 14 provide an outwardly flared portion 15 which is disposed at an angle to the longitudinal axis of said jaw 8.

5 The other end of the strand forming the spring clip 5 constitutes a substantially straight spike-like extension 16 of the opposite end of the coil 6 and which extends outwardly through the jaw 8 between its legs 7 and 10 and to beyond the bend 9. Said end portion 16 constitutes 10 the other spring biased jaw of the clip 5 and preferably terminates in a tapered distal end 17. The jaw 16 is biased in the opposite direction to the jaw 8 by the torsional coil 6, so that said jaw 16 is biased toward the closed side of the recess portion 14 of the jaw 8, its movement toward said closed side of the recess portion 14 being limited by the engagement of an outer portion of the jaw 16 against the bend 9 of the jaw 8. In this normal position of the jaw 16, as illustrated in dotted lines of Figure 1, the leg portions 15 are flared so as to extend across the spike-like jaw 16 and so that the bend or outer end of the jaw 8 is located on the opposite side of the jaw 16 to the rounded leg portions 18 formed by the merging of the inner ends of the leg portions 15 with the outer ends of the recessed portion 14. Said rounded portion 18 of the jaw 8 constitutes a reverse bend to the closed intermediate part of the recessed portion 14.

An end or side edge of a tag, card or label 19 containing any suitable indicia, not shown, may be inserted between the loop end 13 and the adjacent end of the coil 6 20 for passing said loop end 13 through an opening 20 in the member 19 or for punching an opening 20 therein with the loop end 13. The tag or card may then be moved downwardly on the loop 12 from its end 13 to assume its position of Figures 1 and 2, suspended from 25 the clip 5, and it will be readily obvious that the tag or card will not be accidentally disengaged from the clip 5 due to the close proximity of the loop end 13 to the coil 6. If necessary, the end 13 can be sprung away from the coil 6 for attaching the card or tag 19 to the loop 12 or for disengaging it therefrom.

With jaw 16 disposed in its dotted line position of Figure 1, the outer portion of said jaw 16 may be positioned against an element 21 to which the clip 5 is to be attached and so that the element 21 will be to the right of the jaw 16 and in contact therewith and with the bend 9. By 45 then manually moving the clip 5 upwardly, or to the right and then upwardly, the jaw 16 will be sprung from right to left away from the bend 9 from its dotted line position of Figure 1 to and beyond its full line position sufficiently so that the bend 18 is located to the right of the adjacent portion of the jaw 16. It will be obvious that if the clip 5 is moved upwardly as the jaw 16 is thus swung to the left, that the member 21 may pass between the jaw 16 and the bend 18 into the recessed portion 14. 50 By then releasing the clip 5, the jaw 16 will be spring biased from the left to right of Figure 1 to clamp the member 21 in the recessed portion 14. The member 21 will hold the jaw 16 under tension in its full line position of Figure 1 to effectively maintain the clip 5 applied to 55 the member 21. It will also be obvious that as the jaw 16 is displaced away from the bend 9 by the member 21, that the clip 5 may be manually displaced upwardly or toward the member 21 so that said member will engage between the jaw 16 and the jaw portions 15, which are 60 flared outwardly relatively to the jaw 16, to act as a wedge for displacing the outer portions of the jaws 8 and 16 away from one another to allow the member 21 to enter the recess portion 14.

Obviously, other types of elements or members 21 may 65 be similarly connected to the clip 5 which may thus be utilized for attaching identifying tags or cards to various mechanical or electrical parts or for attaching display or

price cards to merchandise. It will also be apparent that the clip 5 may be made in various sizes, depending upon the size of the element or part 21 to be engaged thereby and the size of the tag or card to be supported thereby.

Various other modifications and changes are likewise contemplated and may be resorted to, without departing from the spirit or scope of the invention as hereinafter defined by the appended claims.

I claim as my invention:

1. A spring clip of the character described formed from a single strand of resilient wire having a wound portion defining a torsional coil and including a first loop and a second loop, said coil being disposed between said loops, said loops being formed by a longer end portion of the strand extending from one end of the coil, said first loop including relatively long legs, one of said legs having an inner end merging integrally with one end of said coil, said legs having complementary undulated portions spaced from the ends thereof defining a recess portion opening outwardly of one side of said first loop, the other end of the strand constituting a substantially straight extension of the other end of said coil and extending outwardly therefrom between the legs of said first loop and through the recess portion thereof to beyond the outer closed end of the first loop, said straight extension and said first loop forming coacting clamping jaws spring biased in opposite directions toward one another by said torsional coil, said straight extension engaging the outer end of the first loop in the closed position of the jaws to limit spring biased movement of the jaws in op-

posite directions, said jaws being displaceable away from one another for moving the straight extension to a position to open said recess portion whereby an article to be clamped is insertable therein from between the outer ends of the jaws and whereby the jaws when released will be spring biased for returning the straight extension to a position for closing said recess portion and for clamping the article therein, said second loop constituting an extension of the other leg of the first loop and having end portions thereof located adjacent the ends of the coil, one of said end portions constituting the terminal of the first mentioned end of the strand and being adapted to be passed through an opening of an indicia bearing element for detachably mounting the indicia bearing element on said second loop.

2. A spring clip as in claim 1, said terminal end of the second loop being normally disposed in sufficiently close proximity to an end of the coil to cooperate therewith to prevent casual disengagement of the indicia bearing element from said second loop.
